PROCESS FOR MAKING GAS

Albert R. Stryker, Mariemont, Ohio, assignor of
one-half to Chester Tietig, Covington, Ky.

Application September 30, 1935, Serial No. 42,784

7 Claims. (CL. 48—210)

This invention relates to a process for producing and reforming combustible gases.

Among the objects of the invention are to provide a process for making any gas of predetermined composition and heating value from any carbonaceous volatilizable and combustible material that is capable of being very finely divided throughout a wide range of hydrogen content of such gases.

10 One object is to provide a process for volatilizing hydrocarbonaceous matter for reforming the resulting gas in the same apparatus.

Another object is to provide a process in which the rate and extent of reformation of the gas is 15 under exact control.

Another object is to provide a process in which the carbon produced by reformation of gas is deposited in an advantageous position for its utilization in the further production of gas.

20 Another object is to provide a process for producing industrially pure hydrogen from hydrocarbon raw material.

Another object is to utilize for such purposes certain low grade carbonaceous materials which 25 will be hereinafter mentioned and which have not heretofore been utilizable to produce gases of high heating value or high hydrogen content.

20 My apparatus is an improvement on the subject matter of my U. S. Patent 1,855,034 and the improvement comprises means for obtaining partially or completely reformed gases from various levels of the solid fuel bed, which levels can be easily selected.

Briefly stated, my process comprises passing 35 finely divided volatilizable and/or combustible hydro-carbonaceous material thru a highly heated zone then thru an incandescent bed of solid fuel and cracking the volatile constituents therein and then leading out the gas desired from that level of the fuel bed at which it is formed.

40 Referring to the accompanying drawings, Fig. 1 is a somewhat diagrammatic elevation, partly in section, of a producer-retort according to my invention, and the accessories necessary for its operation.

45 Fig. 2 is a horizontal cross section of the producer-retort along the line 2—2 of Fig. 1 and shows the walls of the fuel zone.

Fig. 3 is a detail in vertical section of the producer-retort taken on the line 3—3 of Fig. 2.

50 Fig. 4 is a front elevation of one of the pierced refractory bricks used at the fuel-zone for leading off the gas.

55 Referring again to Fig. 1, 10 is a retort shell which also serves as the main member of a gas

producer as well as a retort. 10 and its accessories are therefore hereinafter referred to as a producer-retort. The shell 10 has preferably the high, double conical shape shown and in practice may be 80 to 90 feet high and 11 feet in 5 diameter at its widest zone tapering to about 4 feet in diameter at the top. The invention is not limited to such dimensions. The shell is supported by three outside legs which are not shown. Support of this character leaves a free 10 space 11 between the bottom of the shell and a circular wall 12 which surrounds it at the base, and also allows free communication between the inside of the shell and the space within wall 11 which in operation is filled with water. Shell 15 10 is of steel construction and is refractory lined except near the bottom, where there is a zone that is encircled by a water jacket 13. A bed of fuel 17, preferably coal, is carried in the lower conical end up to the line 2—2, i. e., just under 20 an air inlet 14 which is tangential to the shell. At the base of the shell there is a rotary eccentric grate 15, driven by an electric motor 16 and a scraper blade (not shown). The ashes which fall into the space 11 are pushed over the rim 25 of the circular wall 12 into an ash pit as the grate revolves. No novelty is claimed for the rotary grate or ash handling arrangement per se.

Shell 10 is provided with a plurality of inclined ports 18 for charging and maintaining the fuel 30 bed. These are fed with coal from a hopper 19 from which a branched delivery pipe 20 leads, and which ends in a plurality of dump gates 21. From the latter charging buckets 22 can be filled and these can be dumped thru the ports 18 after 35 hydraulically controlled valves 23 covering the ports, are opened. A control board 24 is provided for operating these valves. Such fuel as is charged in thru ports 18 for the purpose of establishing and maintaining the fuel bed, is 40 hereinafter called "maintenance fuel".

At the top of shell 10 is a port 25 thru which solid fuel intended to operate the gas making process is charged. Such fuel may be anything of a hydrocarbonaceous nature and need not be 45 solid. If it is liquid it is charged in thru pipe 26; if it is gaseous thru pipe 27. One or more kinds of fuel can be here introduced together or intermittently or singly. The fuel introduced at the top of the retort for operating the process, I 50 call "operating fuel".

At the upper left side of Fig. 1 there is shown a coal powdering plant 28 which is conventional. It has a delivery hopper 29 for coal dust which dust is transferred to the producer-retort by 55

means of screw conveyor 30. 31 is a motor driven spreader drive. As the dust falls it encounter revolving spreader 32 which can also serve as a valve to close port 25 when desired. Below the 5 top of shell 10 there is an offtake 33 which runs thru a waste heat boiler 34 having a steam drum 35 and a steam delivery pipe 36 in which there is a diaphragm regulating valve 37, said pipe carrying steam to a turbine 67. Offtake 33 runs 10 to a wash box 39 having an outwardly opening hydraulically operated flap valve 40, a gas delivery pipe 41 and a water replenishing and dust disposal system 42. Suitable valves 43 may be arranged in the gas delivery pipe.

15 In the offtake 33 between the top of shell 10 and waste heat boiler 34, there is a hot valve 44, i. e., a valve adapted to operate at high temperatures. It is controlled by a hydraulic cylinder and piston 45 and its function is to close off the 20 offtake 33 during the gas making step of the process.

About the shell 10 at the upper part of the zone of maintenance fuel there is a plurality of circular manifolds 46. Each of these connects 25 to a downcoming manifold 47 and each circular manifold may be shut off from the latter by a valve 48. Each circular manifold taps the shell 10 at four equidistant points. The circular manifolds may be of any selected number, but each 30 is at a different level and connects by means of a short extension 49 to a gas channel 50 which is within the shell 10 at a point below the top of the fuel bed. The inner wall of channel 50 is defined by a circular row or rows of the pierced 35 refractory brick 51, preferably of silicon carbide, one of which is shown in front elevation in Fig. 4 and several in section in Fig. 3 and in plan in Fig. 2.

Each brick or block 51 is provided with three 40 rows of three transverse holes 52. The holes communicate with a longitudinal channel 53 which extends along the rear of the block, this channel constituting a means whereby the gas from the holes 52 may be collected into a single 45 stream. In my apparatus channel 50 may be identical with channel 53 or it may be and preferably is a channel additional thereto but in free communication therewith at all points. Suitable dividing blocks 54 are shown which may also be 50 employed to support the brickwork from the shell 10 and these supports may be of any suitable form. The brickwork is however provided with tongues 55 and grooves 56 which contribute to its stability.

55 The depth of the gas offtakes below the level of the fuel bed is of importance. If a bed of maintenance fuel of 9 to 11 feet deep is used, the top offtake, i. e., the top rows of pierced brick should be from 2 to 3 feet below the top 60 of the fuel bed, the second from 3 to 5 feet below and the third from 5 to 7 feet below.

Beneath the grate 15 there is a generally conical inverted bell 57 into which an air delivery pipe 58 from a blower 59 and a gas exit pipe 60 are fitted. 65 There is also a steam supply pipe 61 fitted into the exit end of the air pipe 58. The latter pipe has a branch 62 which connects with the tangential air inlet 14 above the fuel bed. Both air 70 pipes are provided with shutoff valves 63 and 64 respectively and butterflies 65 and 66 respectively.

A steam supply pipe 72 having a valve 73 is arranged near the top of shell 10 for a purpose later to be described.

75 While my process may be carried out in other apparatus, when it is executed in that shown the operation is as follows:

Lump fuel, preferably coal, but permissibly coke is first charged into the producer-retort and ignited. The degree of subdivision of this fuel should be between pea ($\frac{1}{2}'' \times \frac{3}{4}''$) and furnace lump ($4'' \times 6''$).

After ignition the air blast is turned on from pipes 58 and 62 and the charging process is continued until the fuel bed reaches the desired level, which is thereafter maintained. Secondary air fed in through tangential opening 14 is limited in amount so as to be only sufficient to burn the CO above the fuel bed to CO_2 . Heating is thus continued until the producer retort above the fuel bed is heated at least in part to about 1400°F . plus 400° or minus 100° . During this operation valves 44 and 40 are open permitting smoke to be vented off thru a stack 72 without going thru the water 20 in the wash box. As soon as ash formation or clinker formation begins electric motor 16 is started, thereby rotating eccentric grate 15 so as to catch and crush clinkers between the grate and the shell 10. The scraper blade (not shown) 25 transfers ash from the space between the ring 12 and the shell 10 to an annular ash pit surrounding same.

Enough steam has now accumulated in waste 30 heat boiler 34 to operate exhauster 67 thru its turbine until the next "blow" or heating period. If the quantity of steam should be insufficient auxiliary energy may be supplied from without the system. Exhauster 67 is now started, blower 52 stopped, valves 63, 64 and 44 closed, thereby 35 automatically closing valve 40 and all valves in the gas discharge lines 47, 60 and 41 are opened; those in the latter line at least to some considerable extent.

40 Finely divided operating fuel is now fed from conveyor 30, thru opening 25 into the top of the producer-retort and allowed to fall as freely as it may but still under influence of the suction created by exhauster 67, to the top of the fuel bed. Carbonization and liberation of gas takes 45 place during the descent and after the particles have come to rest on the surface of the fuel bed or in its interstices. Charging of operating fuel is so conducted that a minimum of air is admitted with the fuel, i. e., the sealing and revolving spreading bell 32 is raised to a point that will allow continuous dropping into the producer-retort of the desired amount of fuel with little or no air.

50 Gas delivery pipe 60 runs to a steam-turbine 55 driven exhauster 67 and before it reaches the latter, it is joined by gas delivery pipe 47 from the manifolds 46. From the exhauster pipe 60 extends to the wash box 39.

Steam for driving the exhauster 67 is supplied 60 from the steam drum 35 of waste-heat boiler 34 thru a pipe 68 in which there is a diaphragm-controlled spring loaded regulating valve 37 shown in exaggerated size on Fig. 1. This valve is conventional and may be either the one sold 65 by the Chaplin-Fulton Mfg. Co. of Pittsburgh, Pa., under the name of "Duplex Steam Control for Gas Producers" or that made by the Fisher Governor Co. of Marshalltown, Iowa, as Type 1560, "Low Pressure Diaphragm Actuated Valve." 70

From the diaphragm chamber 70 of valve 37 a pressure-communication pipe 71 runs to the interior of shell 10 to a point just above the fuel bed. The valve 37 is so arranged that the interior of shell 10 shall maintain as closely as pos- 75

sible a minus pressure of 0.2 inch of water. This value may be varied at the will of the operator, but is recommended for ordinary operation. The valve regulates the steam supply to the exhauster turbine so that if the pressure in shell 10 rises to an undesired value, more steam will be admitted to the turbine, the exhauster will increase its speed and consequently lower the pressure within the shell 10.

10 The level of the fuel bed from which the gas is to be taken is selected by opening the valves 48 at the levels desired to withdraw gas thru the holes and channels in the pierced bricks or opening a valve 73 in line 60. Any desired blend 15 of gas may be made by regulating valves 48 or 73 and if desired also by the use of a valve 74 in pipe 47. The lower the level selected, the higher will be the hydrogen content of the gas and if the entire depth of bed is utilized by with- 20 drawing gas exclusively from the bell 57, industrially pure hydrogen will be the product. In any case the gas output passes thru a portion of pipe 60 below the exhauster and the remainder of said pipe above the exhauster to be washed in wash 25 box 39 and to make its exit from pipe 41.

The operating fuel may be any kind of coal, anthracite, bituminous, lignite, mine refuse and off season stocks. It may also be petroleum oil or its fractions including fuel oil, gas oil, still 30 bottoms, gasoline, kerosene, butane, ethylene and others. Natural gas and refinery gas may be used since, while these substances undergo a diminution of heating value when put thru my process, they also undergo a considerable permanent ex- 35 pansion in volume. Wood fiber, straw, corn stalks, cocoanut, cottonseed oil, animal fats, fatty acids, residues from fatty acid distillation, spoiled fats and any hydrocarbonaceous material capable of being finely divided to particles of say $\frac{1}{6}$ " 40 square or smaller, can be used. The term "hydrocarbonaceous" as I use it includes fatty carbohydrates.

If freedom from by-products (tars, light oil, etc.) which might clog city gas lines, is desired 45 the lower level of the fuel bed should be selected as the source of the gas. The lower the level selected, however, the lower will be the heating value of the gas obtained, the greater the freedom from by-products, the higher the hydrogen 50 content and the greater the permanent gas volume.

For the production of city gas, of highest heating value, the preferred method would be to take gas only from the top offtake. For a gas of 55 fairly low heating value but carrying little or no by-products, gas from the middle or lower side offtakes is to be chosen. For the production of all hydrogen for process work or for mixing with other gases for transportation, the offtake below 60 the grate is to be selected.

In the case of reformation of gaseous fuels, with a temperature of 1500° F. at first or top offtake a 650 B. t. u. coal gas may be cracked back to 600 B. t. u.

65 With the same temperature at first offtake and 1700° F. at the second, a 650 B. t. u. gas may be cracked back to 500 B. t. u.

With the above temperatures at the first two offtakes and 2000° F. (partially in the incandescent zone) at the third, a 650 B. t. u. gas may be cracked back to 400 B. t. u.

70 Lastly, by drawing the gas thru the entire incandescent zone (2600°-2800° F.) thru the bottom offtake, the gas may be completely cracked 75 to approximately 325 B. t. u. which is an indi-

cation of its nearly pure hydrogen composition.

While the operation of my apparatus is continuous during the gas making period, that period lasts only until there is insufficient heat left in the upper walls of the producer-retort to drive off the volatile matter from the operating fuel dropped past them. When this occurs, the exhauster 61 is either shut down or valved off. Valves 74 and 73 are preferably closed, ports 18 and 25 are closed and hot valve 44 is opened. 10 Valves 43 are closed. Blower 59 is started and air fed to the producer-retort both above and below the fuel bed. The tangential inclination of port 14 causes the air to have a scouring action on the walls of the retort and thus any carbon 15 clinging to the retort walls is efficiently burned. The hot gases produced by the combustion find their exit thru the offtake or leading off means 20 33 and in doing so heat the water in wasteheat boiler 34 and so to wash box 39. Here, because the gases are under considerable pressure hydraulically operated valve 40 opens and the gases with accompanying smoke and dust, pass up the stack 72.

A number of common and well known types 25 and combinations of types of gases may be produced in addition to the gases hereinbefore mentioned. The producer portion of the apparatus may make either air blown or steam producer gas independent of or in combination with partially 30 or wholly reformed hydrocarbon gas, by blowing air only or air and steam through air inlet 58 and steam supply line 61. All other connections remain closed with the exception of offtake valve and offtake pipe 33 permitting a free flow of pro- 35 ducer gas to the washbox.

Straight blue gas or combinations of blue gas, producer gas and partially or wholly reformed gas may be produced by passing steam only through the heated fuel bed through steam supply line 61, and blue gas thus generated is removed to the washbox, through offtake 33 or steam may be admitted to the upper portion of the retort through seam connection 72 passing downwardly through the fuel bed and leaving 45 the gas offtake below the grate and allowed to flow under its own pressure through exhauster 61 and into pipe 60 to the washbox.

Oil gas may also be produced by spraying oil into the upper reaches of the heated retort 50 through pipe 26. With hot valve 44 open and all other connections closed the oil gas thus produced must pass through the washbox under its own pressure.

Oil gas can further be produced and utilized to 55 carburet or enrich producer gas or blue gas before described.

It is evident that if any of the gases described or any combination of gases described can be utilized either separately or in combination with 60 the process of cracking hydrocarbon-gas that carbon deposited in the fuel bed due to cracking and also residues from solid operating fuels may be utilized for the production of gas or merely 65 for the heating of the retort.

Due to the fact that secondary air blast connection 14 is tangential to the shell of the retort and a swirling motion is imparted to the air it is possible to properly manipulate butterfly valves 70 65 and 66 (after ignition is attained above the fuel bed) to pick up solid residue deposited on the top of the fuel bed after a gas "run" and burn the finely divided fuel within the retort much the same as firing a boiler with powdered fuel. The 75

products of combustion and ash leave through the offtake 33 and are vented to the air through stack 72.

I claim as my invention:

- 5 1. That step in the process of making a combustible mixture of gases comprising free hydrogen which comprises dropping finely divided solid hydrocarbonaceous matter thru a space hot enough and deep enough to volatilize substantially all of the gas producible by the pyrolysis of said matter and withdrawing the gas so produced from a selected level of a fuel bed maintained at least in part at incandescence at the bottom of said space from a region below the upper surface of said bed.
- 10 2. That step in the process of making a combustible mixture of gases comprising free hydrogen which comprises dropping finely divided hydrocarbonaceous fuel thru a space hot enough and long enough to volatilize substantially all of the volatile constituents thereof which can be freed by the pyrolysis of the said fuel, maintaining a bed of operating fuel at least in part at incandescence at the lower end of said space and withdrawing the said gas from a region below the top of said fuel bed from the sides thereof also, simultaneously, from below the bottom of said fuel bed and mingling the two currents of gas so withdrawn.
- 15 3. The process of cracking gas which comprises directing a stream of hydrocarbonaceous crackable gas downward thru a bed of fuel hot enough to crack said gas and deep enough and composed of particles fine enough to retain most of the carbon generated by the reaction and then removing gas which has been cracked to the extent desired from a selected level and from the sides of said fuel bed, while preventing further contact of the gas with the fuel bed during the step of removal.
- 20 4. The process which comprises bringing a bed of lump fuel to incandescence and the space above it to a temperature of at least 1400° F. dropping finely divided hydrocarbonaceous fuel on the top of said bed thru the heated zone 5 above same, withdrawing combustible gas produced by the pyrolysis of said fuel from a pre-selected level below the top of said bed of lump fuel and from the side thereof, the gas from each region varying in hydrogen content from 10 that withdrawn from the other regions.
- 25 5. The process which comprises dropping thru a pyrolyzing zone a finely divided hydrocarbonaceous solid fuel onto a bed of lump fuel at least partially at incandescence, said bed being 15 composed of particles not smaller than pea size coal and not larger than lump coal, the bed being adapted to retain the greater part of the solid residues of cracking of said finely divided fuel within the interstices of the bed, and then 20 withdrawing from a selected region in said bed a stream of gaseous products of pyrolysis at a low velocity from the sides of said bed.
- 30 6. A process according to claim 5 in which the operations of gas generation and withdrawal are 23 conducted at a pressure slightly below atmospheric.
- 35 7. That step in the process of making a mixture of gases comprising free hydrogen, which comprises dropping finely divided hydrocarbonaceous fuel thru a space hot enough and long enough to volatilize substantially all of the volatile constituents thereof which can be freed by the pyrolysis of the said fuel, maintaining a bed of operating fuel at least in part 33 at incandescence at the lower end of said space and withdrawing the said gas from a region below the top of said fuel bed from the sides thereof.

ALBERT R. STRYKER. 40
